Primary Examiner — Carla Jobe Wright(74) *Attorney, Agent, or Firm* — Banner & Witcoff, Ltd.(57) **CLAIM**

The ornamental design for a handset cover, as shown and described.

DESCRIPTION

FIG. 1 is a front perspective view of a handset cover showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of a handset cover and the unshaded regions therein are for environmental purposes only and form no part of the claimed design.

1 Claim, 5 Drawing Sheets(56)
